UNITED STATES PATENT OFFICE.

GEORGE LEWIS PRATT, OF ATLANTA, GEORGIA.

POR-T-CLOSING DEVICE.

No. 826,060.

Specification of Letters Patent.

Patented July 17, 1906.

Application filed August 14, 1905. Serial No. 274,209.

To all whom it may concern:

Be it known that I, GEORGE LEWIS PRATT, a citizen of the United States, residing at Atlanta, in the county of Fulton and State of Georgia, have invented certain new and useful Improvements in Port-Closing Devices; and I do hereby declare the following to be a full, clear, and exact description of the invention, such as will enable others skilled in the art to which it appertains to make and use the same.

Much difficulty has been experienced in the past in pulverizing machines or mills and the like placed side by side in a chain or gang and having, perhaps, only one common connected chamber to receive the pulverulent material coming from the mills of back draft and consequent sifting of dirt into and up through a machine which may be temporarily idle in the series or gang, thus undesirably and unnecessarily clogging the working parts thereof.

The object of my invention, therefore, is in a simple and efficient manner to remedy this difficulty by preventing such back draft and consequent sifting of dirt into and up through the mill while the same is idle.

With this object in view the invention consists in the novel construction, combination, and arrangement of parts, as will be herein-after fully described and claimed.

In the accompanying drawings, forming part of my specification, I have shown my invention applied to a pulverizing mill or machine, it being understood that I do not confine its application to use in such connection, as it can be used wherever desired.

In the drawings, Figure 1 is a central vertical section through a form of pulverizing machine, showing the application of my invention thereto. Fig. 2 is a fragmentary view in top plan of my invention, showing the slide-member ports fully registering with the base-ports. Fig. 3 is a view similar to Fig. 2, but showing the slide member shifted, so that its ports are not in full, but only partial, register with the ports in the base; and Fig. 4 is a fragmentary vertical section taken on line *a a*, Fig. 2.

Referring to the drawings in detail, A designates a pan for the reception of the material to be pulverized and being preferably circular in shape. In this pan work rollers B, carried by shafts C, as usual, a wear-ring D being preferably disposed within the pan, against which the rollers operate.

Adjacent to or formed as a part of pan A is a base F, provided with ports *h* therethrough. Around the upper outer edge of the base is secured an annular upright drum *f*, confining dust and pulverulent material, issuing through a conical screen E, secured around the top of the pan to the interior of the pulverizing-mill and directing such pulverulent material so passing through said screen downward through ports *i* (hereinafter more specifically mentioned) and *h* and preventing the pulverulent material from sifting in all directions exterior of the pulverizing-mill.

Disposed between the drum F and the screen E, and preferably supported on top of the base F and the pan A, is a slide member I, preferably ring or circularly shaped and provided with port-holes *i* therein, adapted to register with ports *h* through base F. Carried by the slide member I is a rack *i*².

Suitably journaled in the base F is a shaft J, carrying at its outer end appropriate means for its rotation, as a hand-wheel *j*, and at or near its inner end a pinion *j*², meshing with rack *i*². When slide member I is in the position shown in Fig. 2, port-holes *i* therein and ports *h* in base F are in register, and passage therethrough is permitted to a suitable compartment or receptacle. (Not shown.) A revolution of hand-wheel *j* will blank such port-holes and ports.

As there may be a tendency to lift or rise on the part of the slide member I under certain conditions, as when moved, as described, and as there is also necessarily some friction or binding of the same when in operation, I overcome these tendencies by a combined guard and antifriction device, which may be as follows: Revolvably mounted on screw-pins *k*, (preferably three in number,) set in top of pan A or in top of base F, or in both pan and base, adjacent the edge of slide member I, are rollers K, in juxtaposition to the edge of the slide member and having annular flanges *k*² overlying slide member I and constituting guards acting at all times to prevent the slide member from rising or lifting. It will be seen that the revolvably-mounted rollers K prevent any possible binding or friction, which would otherwise occur, thus obviating wear and rendering easy the operation of the slide member.

In the operation of the machine as the material is ground in pan A by the rollers working therein it is continuously thrown up

against screen E and the finer particles thereof of sift through the screen and thence through registering port-holes *i* and ports *h* to a receiving-compartment. Should the mill be 5 idle, hand-wheel *j* is revolved to the right, say, whereupon all port-holes and ports are blanked, preventing any back draft and consequent sifting of fine dust and dirt up through ports *h* and into the idle mill, such 10 back draft being caused by the other working machines in the gang which dump into one common receiving-compartment pulverulent material.

My device is thus exceedingly simple in 15 construction and most efficient in operation and adds materially to the value of any pulverizing-mill, to which it may be readily applied.

As many minor changes may be made in 20 the details of construction, I do not wish to be limited to the exact construction shown.

Having thus fully described my invention, what I claim as new, and desire to secure by Letters Patent, is—

25 1. In a pulverizing machine or mill, a pan adapted for the reception of the material to be pulverized, and within which work the usual crushing-rollers, a base in juxtaposition to the outer edges of such pan and having 30 ports therethrough, an upright surrounding drum or casing secured to the upper edge of the base, a slide member disposed within the space inclosed by the surrounding drum or casing, and having ports therethrough adapted 35 to register with the ports in the base, and also having a rack on its under surface, and a rotatable shaft journaled in the base and provided toward its inner end with a pinion disposed beneath said slide member and adapted 40 to mesh with its rack.

2. In a pulverizing machine or mill, a pan adapted for the reception of the material to be pulverized, and within which works the usual crushing-rollers, a base in juxtaposition 45 to the outer edges of such pan and having ports therethrough, an upright surrounding drum or casing secured to the upper edge of the base, a slide member disposed within the space inclosed by the surrounding drum or 50 casing, and having ports therethrough adapted to register with the ports in the base, and also having a rack on its under surface, a rotatable shaft journaled in the base and provided toward its inner end with a pinion dis-

55 posed beneath said slide member and adapted to mesh with its rack, and antifriction devices disposed intermediate the base and the slide member.

3. In a pulverizing machine or mill, a pan 60 adapted for the reception of the material to be pulverized, and within which work the usual crushing-rollers, a base in juxtaposition to the outer edges of such pan and having ports therethrough, an upright surrounding 65 drum or casing secured to the upper edge of the base, a slide member disposed within the space inclosed by the surrounding drum or casing, and having ports therethrough adapted 70 to register with the ports in the base, and also having a rack on its under surface, a rotatable shaft journaled in the base and provided toward its inner end with a pinion dis-

75 posed beneath said slide member and adapted to mesh with its rack, and means for holding the slide member against upward movement.

4. In a pulverizing machine or mill, a pan 80 adapted for the reception of the material to be pulverized, and within which work the usual crushing-rollers, a base in juxtaposition to the outer edges of such pan and having ports therethrough, an upright surrounding drum or casing secured to the upper edge of the base, a slide member disposed within the space inclosed by the surrounding drum or 85 casing, and having ports therethrough adapted to register with the ports in the base, and also having a rack on its under surface, a rotatable shaft journaled in the base and provided toward its inner end with a pinion disposed beneath said slide member and adapted 90 to mesh with its rack, and combined antifriction devices and guards for holding the slide member against upward movement.

5. In a pulverizing machine or mill, a pan 95 adapted for the reception of the material to be pulverized, and within which work the usual crushing-rollers, a base in juxtaposition to the outer edges of such pan and having ports therethrough, an upright surrounding 100 drum or casing secured to the upper edge of the base, a slide member disposed within the space inclosed by the surrounding drum or casing, and having ports therethrough adapted to register with the ports in the base, and also having a rack on its under surface, a rotatable shaft journaled in the base and provided toward its inner end with a pinion disposed beneath said slide member and adapted 105 to mesh with its rack, and antifriction devices, comprising screw-pins set in the upper edge of the base, and rollers revolvably carried thereby and bearing against the edge of the slide member.

6. In a pulverizing machine or mill, a pan 115 adapted for the reception of the material to be pulverized, and within which work the usual crushing-rollers, a base in juxtaposition to the outer edges of such pan and having ports therethrough, an upright surrounding 120 drum or casing secured to the upper edge of the base, a slide member disposed within the space inclosed by the surrounding drum or casing, and having ports therethrough adapted to register with the ports in the base, and also having a rack on its under surface, a rotatable shaft journaled in the base and provided toward its inner end with a pinion disposed beneath said slide member and adapted 125 to mesh with its rack, and combined anti- 130

friction devices and guards for holding the slide member against upward movement, comprising screw-pins set in the upper edge of the base, and rollers revolubly carried thereby and bearing against the edge of the slide member, and having annular flanges overlying the slide member.

In testimony whereof I affix my signature in the presence of two subscribing witnesses.
